CENTRIFUGAL PUMP

John Mann, Seneca Falls, N. Y., assignor to
 Goulds Pumps, Inc., Seneca Falls, N. Y., a corporation of New York

Application July 9, 1937, Serial No. 152,801

2 Claims. (Cl. 103—97)

My invention relates to new and useful improvements in centrifugal pumps. Heretofore it has been necessary for a manufacturer of pumping equipment, if he wished to compete with his competitors in the matter of quick deliveries upon orders received, to maintain a large stock of pumps on hand. Usually the manufacturer kept in stock a range of sizes of pump casings and an innumerable number of pump impellers, each having different operating characteristics. Upon receipt of an order for a pump, in accordance with certain specifications, the manufacturer selected the proper size of casing and mounted therein the impeller most nearly adapted to obtain the characteristics, as to fluid capacity and pressure head, required. Not only did this compel the manufacturer to maintain a large inventory of pump casings and impellers, but also, particularly in the case of pumps for small capacities, the efficiency of the average resulting pump was comparatively low because a pump and its impeller for the best operating characteristics and efficiency, must be designed for each other. The maintenance of a large stock of pump casings and impellers is a distinct hardship on the manufacturer and is particularly necessary in pumps for small capacities because the customer, due to the small size of the pump, expects shipment substantially upon receipt of the order.

In addition, centrifugal pumps, except centrifugal pumps of special design, in the past have been primarily used where a large volume of liquid was to be pumped at reasonably low pressures or where a small volume of liquid was to be pumped at relatively low pressures. Where higher pressures were desired, particularly at small capacities, other types of pumps have been used—usually a positive displacement pump. Probably, the reason why centrifugal pumps have very rarely been used for small capacities, 100 gallons per minute or less, at relatively high pressures, one hundred and fifty to two hundred and fifty feet total head, is because the leakage factor, while relatively unimportant in large capacity pumps, is a significant factor in reducing the efficiency of small capacity pumps. To provide an efficient small capacity centrifugal pump capable of developing relatively high pressures required a hand-tailored pump, the manufacturing expense of which did not admit of its being sold in competition with other types of pumping equipment.

An object of my invention is to provide a compact pumping unit so constructed and arranged that the fluid capacity and pressure head of the

pump, within limits, may be readily varied while still maintaining the pump at relatively high efficiency, whereby without maintaining an abnormally large stock of pumps, a wide range of operating conditions may be met.

Another object of my invention is to provide a centrifugal pump which may be readily converted into a pump having different operating characteristics.

Another object of my invention is to provide a centrifugal pump so constructed and arranged that the fluid capacity and pressure head, of which the pump is capable, may be varied over rather wide limits.

Another object of my invention is to provide means whereby the volume of the casing, into which liquid is discharged by the impeller vanes, may be varied in volumetric capacity and in cross sectional area, particularly at the throat thereof, to thereby vary the fluid capacity and pressure head of the pump.

Another object of my invention is to provide a small capacity relatively high pressure centrifugal pump which is efficient in operation and which may be manufactured and sold at a reasonable cost.

My invention further contemplates the provision of novel means for sealing the impeller drive shaft to protect the shaft from the corrosive and abrasive action of the liquid being pumped.

My invention, in addition, contemplates the provision of means for minimizing leakage from the high to the low pressure side of the pump, whereby to increase the efficiency thereof.

Other objects and advantages of my invention will be more apparent from the following description when taken in connection with the accompanying drawings, in which:

Figure 1 is a view showing the pump and motor assembly.

Figure 2 is a sectional view showing the pump casing, the impeller, the stuffing box assembly and other parts of my novel pumping unit.

Figure 3 is a view taken on the line 3—3 of Figure 2.

Figure 4 is a partial view, similar to that of Figure 3, showing the cover plate of the pump casing rotated to decrease the cross sectional area of the casing volume.

Figure 5 is a development of the pump casing volume.

Figure 6 is a view taken on the line 6—6 of Figure 2 showing the manner in which the wear-ring rings are locked in the casing.

Figure 8 is a view taken on the line 8—8 of Figure 2 showing the means for sealing the impeller shaft.

Figure 9 is a view showing a pump impeller in which the hub of the impeller is solid instead of perforated as shown in Figures 2 and 8.

Figure 10 is a view showing pump characteristic curves.

Figure 11 is an enlarged view of a portion of Figure 2 showing a possible position of the wearing ring.

The features of my invention, while they may, for the most part, be embodied in any type of centrifugal pump, are particularly adapted for incorporation in what is known in the art as a "close coupled" pump. The primary differences between a close coupled pump and other types of centrifugal pumps are that, in a close coupled pump, the motor and pump casings are, by what is known as an adapter, rigidly secured closely together and the drive shaft is common to both the motor and the pump.

As shown in Figure 1, the assembly, in which the novel features of my invention are incorporated, comprises a motor 11 having suitable pedestals 12 by which the unit may be supported on the floor or other support, an adapter 13 and a pump casing generally indicated by the numeral 14. The adapter is provided with hand holes to enable access to the stuffing box unit. The adapter, as shown in Figure 2, is rigidly bolted, as indicated at 16, to the motor casing, and the pump casing is in turn rigidly bolted, as indicated at 17, to the adapter. A third pedestal 18 is provided for supporting the unit on the floor or other support. Any suitable means may be provided for rigidly securing the pump and its motor to the floor, no special foundation being required with this type of pump. If desired, the pump unit may be secured in a vertical position as the unit is particularly adapted to operate in any position.

The pump casing comprises a casing proper 19 and a cover plate 21 which may be bolted thereto as indicated at 22. The shaft 23, which is common to both the motor and pump, has a suitable bearing 24 at the pump end of the motor casing and another bearing (not shown) at the other end of the motor casing. That portion of the shaft 23 which extends beyond the motor casing 11 is overhung and extends through the adapter and into the pump casing 14. To the end of the shaft 23, by means of a key 24', is secured, against rotation with respect to the shaft, the hub 26 of an impeller 27. The impeller is usually made of bronze and is held in position on the shaft by means which will be later described.

The impeller comprises a web 28, a plurality of vanes 29 cast integrally with the web 28 and a shroud 31 which may be riveted or otherwise secured to the vanes, as indicated at 32. While I have shown and described the impeller as being made in separate parts and then secured together, it will be appreciated that the web, the blades and the shroud may be cast integrally. The main advantage of casting the web and the shroud separately is to enable the impeller to be more easily machined or filed to provide smooth water passages. If the impeller is rather wide, of course, it may be more cheaply cast integral.

The shroud, as it approaches the impeller axis, curves outward as indicated at 33 to form a smooth entrance for fluid into the impeller, com-

monly called the eye of the impeller. At its central portion, the shroud is flanged outward, as indicated at 34, to provide a fluid entrance or suction opening into the impeller. The suction pipe 36 is threaded, as indicated at 37, in an opening in the cover plate 21 and is in axial alignment with the flange 34 of the impeller so that fluid being drawn through the suction pipe, or flowing thereto by gravity, will smoothly enter the eye of the pump impeller. If desired, instead of using threaded connections between the suction pipe and the cover plate, flanged connections may be used.

The cover plate 21 has an inwardly directed flange 38 which is preferably formed on the arc 15 of a circle and which extends substantially three-fourths of the distance around the cover plate, as shown in Figure 3. This flange is of such width that, when the pump is assembled, its edge butts against the wall 39 of the casing proper 19. The impeller 27 is concentric with and somewhat smaller in diameter than the flange 38 to provide clearance 41 around the impeller. The internal bore of the casing proper 19 and the flange 38 are concentric except that the casing wall, beginning at the point 42, merges into what is known in the art as a casing volute 40. The volute portion of the casing is in open communication with the impeller, extends from the point 42 and gradually increases in width and depth to the point 43. The volute may be either rounded in cross section or substantially square as shown at 45 in Figure 2. The function of the casing volute is to convert the velocity head of the liquid, imparted to it by the impeller, into pressure head. From the point 43 the volute merges smoothly into a discharge opening 44 formed in the casing proper 19. The point of merger of the volute with the discharge outlet is known as the "throat" of the volute or the point of "cut water." The discharge opening 44 is substantially circular in cross section, the cross sectional area gradually increasing toward the outlet. In the discharge opening, in any suitable manner, is secured a discharge pipe 46.

In my close coupled pump, the discharge pipe 46 may be located in any one of four positions. Two of the positions are indicated in Figure 3, one in solid lines and the other in dotted lines. This may be accomplished by shifting the entire pump casing 14 with respect to the adapter 13 and bolting the pump casing to the adapter in the desired location by means of bolts one of which is indicated at 17. The fact that the entire pump casing may be shifted to different discharge positions is of particular advantage in enabling the discharge pipe to be secured to the discharge opening of the pump conveniently and with as few bends in the discharge pipe as need be.

The capacity of a pump and the pressure of liquid which it is capable of developing are known in the art as the characteristics of a pump. When the capacities and heads of which the pump is capable are plotted on graph paper, there is obtained what is known as a pump head-capacity characteristic curve. One of the features of my invention is the means by which the pump of my invention may be converted, without substituting any new parts or modifying any of the parts of the pump, into a pump having different operating characteristics or rather a pump for which, by proper adjustment, a number of different characteristic curves may be plotted. This is accomplished by rotating the cover plate 21 with respect to the casing proper 19 and bolting

the cover plate to the casing proper in the desired location by means of the bolts, indicated at 22.

Shifting the cover plate in a clockwise direction, as viewed in Figure 3, moves the flange 38 so as to decrease the area of the throat of the volute or the maximum cross sectional area of the volute 40 and, of course, its volumetric capacity. A position to which the flange 38 may be shifted has been shown in Figure 4. From that figure, it will be apparent that the area at 48, the throat of the volute or the point of cut-water, is less than the area at 43 of Figure 3, the point of cut-water with the flange in its normal position. It will further be apparent from Figures 3, 4 and 5, the latter of which is a development of the volute, that the area at the throat of the volute, by properly positioning the flange 38, may be made any desired amount. The discharge of water from the pump may even be entirely cut off by shifting the flange 38 in a clockwise direction so that the point 38' of the flange is shifted to or beyond the point 42 of Figure 3.

The practical effect of decreasing the throat area of the volute may be made clear from Figure 10 which shows what have been described above as "pump characteristic curves". We will assume that curve A is the head capacity curve of the pump described above and shown in the drawings with the flange 38 in the position shown in Figure 2; that is, with the throat area at its maximum. The pump casing and impeller are designed to obtain maximum pump efficiency with maximum volute throat area. Curve B, we will assume, is the efficiency curve of the pump shown and described, and curve C shows the brake horsepower required to drive the pump. The total head in feet, the brake horsepower and efficiency are graduated along the axis of ordinate and the capacity of the pump in gallons per minute is graduated along the axis of abscissa. In practice, these curves are found by throttling the discharge valve or, in other words, varying the pump discharge pipe opening and by proper measurements, well known in the art, determining various head-capacity points and brake horsepower points which are plotted on graph paper. After sufficient points have been plotted, curve A, representing the head-capacity characteristic curve, and curve C, representing the brake horsepower, are drawn. From these two curves, the efficiency of the pump may be calculated for any condition by formulae, not necessary to be set forth herein.

Considering curve A, any condition along line A may be obtained by regulating or throttling the discharge valve, indicated at 49. For example, by properly regulating the discharge valve, the pump may be set to deliver forty-eight gallons per minute against a total head (static head plus friction) of seventy feet. This condition is shown at point D on curve A. Under these conditions, the efficiency of the pump and the brake horsepower required to drive the pump, found on curves B and C directly below point D, will be respectively approximately 52% and 1.6 horsepower.

In the centrifugal pumps of the prior art, if conditions of head and capacity were specified by the customer not found on curve A, another pump would have to be used—one having different operating characteristics, although there are several ways, not necessary to be described herein, of changing, within limits, the characteristics of a given pump.

My invention involves varying the characteristics of a pump by changing the throat area of

the volute. This is accomplished in the pump of my invention, as stated above, by shifting the position of the point 38' of the flange 38. The effect of this may be made more clear from a consideration of Figure 10. We will assume that E, F and G are the head-capacity, efficiency and brake horsepower curves, respectively, of the pump described above with the flange 38 in the position shown in Figure 4, in which position the volute throat area is considerably less than when the flange is in the position shown in Figure 2. By throttling the pump with the flange in the position shown in Figure 4, any condition of head-capacity can be obtained along the curve E. For example, let us assume that, instead of the conditions 48 gallons per minute at 70 feet total head given above, a customer had desired a pump capable of delivering 16 gallons per minute at a total head of 70 feet. This condition appears on the curve E at the point H. Reading below the point H on the curves F and G, it is found that the brake horsepower required to drive the pump is approximately .9 horsepower and the efficiency of the pump is approximately 32%.

It will now be appreciated that, with the same casing and impeller, by shifting the flange 38 to the proper position, various characteristic curves similar to curve E may be obtained. This eliminates the necessity of maintaining a large stock of pump casings and impellers on hand. With a limited number of pumps in stock, a wide range of operating characteristics may be obtained. Moreover, it is possible by my invention to make the volute throat exceedingly small in area, without the necessity of attempting to cast volutes with small throat areas which is impractical. In practice, casings with small volute throat areas cannot be cast and must be machined.

One of the most important factors adversely affecting the efficiency of a centrifugal pump is the leakage of liquid which occurs from the high pressure side of the impeller to the low pressure side thereof; that is, between the impeller flange 34 and the casing from the space 51 surrounding the impeller to the suction inlet. The energy applied to this leakage liquid is wasted. To minimize this leakage and to prevent casing wear, it is customary to employ what are known in the art as casing wearing rings. These casing wearing rings are usually fitted to and rigidly held in the casing and the impeller rotates with respect to them.

In my pump construction, to limit the amount of leakage, I employ a wearing ring 52 of novel design. Pump wearing rings are usually made of bronze, although other materials can and have been employed. The wearing ring 52 is generally L-shaped in cross section, as shown in Figure 2, comprising a sleeve portion 53 and a portion 54 extending at right angles thereto. The sleeve portion is made relatively long, as at a given pressure, the leakage is substantially inversely proportional to the length of the wearing ring. That is, with a given clearance between the wearing ring and the flange of the impeller and a given flange diameter, the leakage from the high to the low pressure side of the impeller is decreased upon increasing the length of the running fit between the sleeve and the impeller flange.

In most wearing ring constructions, it is necessary to provide an appreciable diametral clearance between the sleeve and the impeller flange, of the order of ten to twenty thousandths of an

inch, because the pump shaft, particularly when overhung, has a tendency to whip and rotate, at times, slightly off center. In a pump of large capacity, this amount of clearance, although made as small as possible, is not of significant importance because the leakage is but a small percentage of the volume of liquid pumped. However, because, other factors being the same, the amount of leakage is substantially proportional to the pressure and substantially independent of the volume of the liquid being pumped, the leakage factor is very important in small capacity pumps. A leakage of ten gallons per minute is relatively unimportant in a pump having a capacity of a thousand gallons per minute, but a leakage of ten gallons per minute in a pump having a capacity of forty gallons per minute means a loss of pump efficiency from this source alone of twenty-five per cent.

20 In accordance with my invention, the diametral clearance between the sleeve 53 and the flange 34 is made approximately five thousandths of an inch which appreciably decreases the leakage from the high pressure to the low pressure side as, in general, the leakage is proportional to the area of the annular opening between the sleeve and the flange of the impeller. Moreover, the shaft diameter and the weight of the impeller are selected and matched so that the maximum 25 deflection of the shaft will not exceed one thousandth of an inch which is insufficient to cause the shaft to whip or rotate off center. Further, I provide additional diametral clearance between the external circumference of the sleeve and casing, as indicated at 61, which may be approximately five to ten thousandths of an inch.

In order that this additional clearance at 61 shall be available when required, the wearing ring 52 is permitted to float freely between the impeller flange 34 and the casing. If the shaft rotates off center or is slightly sprung, or if the parts such as the impeller and casing are not assembled concentric, the wearing ring can adjust itself to center around the impeller flange. To prevent leakage of the fluid being pumped, from the high pressure side of the impeller to the low pressure side thereof between the wearing ring and the casing, the wearing ring is free to be pressed against the casing by the pressure of liquid in the discharge chamber 51. To increase the effect of this pressure, the portion 54 of the wearing ring is provided with an annular sealing surface 62, as more clearly shown in Figure 11. This annular sealing surface is of small area. By reason of the pressure existing in the chamber 51, when the pump is operating, the wearing ring is pressed toward the left, as viewed in Figure 2, so that the annular sealing surface 62 is pressed into sealing engagement with the interior of the cover plate. The pressure between the sealing surfaces will be the pressure of the liquid being pumped multiplied by the effective area of the wearing ring exposed to discharge pressure less the pressure on the suction side of the wearing ring times the effective area of the wearing ring exposed to suction pressure divided by the area of the annular sealing ring.

70 Of particular importance in the construction of my novel wearing ring is the fact that the wearing ring is free to float and will normally remain concentric with the shaft sleeve, the additional clearance at 61 being available to permit the wearing ring to adjust itself to compensate for any

eccentricity of the mating parts, such as between the impeller flange 34 and the bore of the casing, and maintain a uniform clearance between the impeller flange 34 and the bore of the wearing ring 52. While, in general, I am aware that the use of floating wearing rings has been considered before, I am aware of no wearing ring in which the importance of the clearances, above specified is recognized and in which the seal between the casing and the wearing ring is accomplished in the manner above described. Particularly, I am aware of no wearing ring in which the ring is locked in the casing to prevent its rotation with the pump impeller. In the floating wearing rings with which I am familiar, the wearing ring is free to rotate with the impeller and is likely to jam against the casing or impeller. In my construction, as shown more clearly in Figure 6, I provide on the wearing ring a lug 63 which registers with a notch 64 in the casing to prevent the wearing ring from rotating with the impeller and yet permit the ring to float freely.

In Figure 11, which is an enlarged view of a portion of the impeller and wearing ring of Figure 2, I have shown the wearing ring in engagement with a shoulder 67 on the impeller, a possible position of the wearing ring when the pump is not primed and there is no pressure difference between the discharge chamber 51 and the suction side of the impeller. With the wearing ring in this position, an annular throttling space or port 68 is provided between the wearing ring and the bore of the casing through which leakage from the chamber 51 to the suction side of the impeller may freely occur.

With the wearing ring in the position shown in Figure 11, when the pump is primed and develops discharge pressure, the capacity of the pump is sufficiently large that the leakage through the annular space 68 is not sufficient to drop the pressure in the chamber 51 appreciably. The leakage is also insufficient to build up any appreciable pressure in the suction chamber of the pump. Consequently, there is an unbalanced pressure area on the two sides of the wearing ring. That is, that portion of the area of the wearing ring represented by the difference in diameters K and L does not have equal pressures on opposite sides thereof for the reason that the pressure in chamber 51 is greater than the pressure in the suction chamber. Consequently, as the pressure in chamber 51 builds up, the wearing ring will move to the left, as viewed in Figure 11. The annular sealing surface 62 will then engage the casing and cut off the leakage through the throttling port 68. It is important that the parts be so constructed and arranged that the wearing ring cannot move sufficiently far to the right, as viewed in Figure 11, to permit open access between the discharge chamber 51 and the suction chamber. That is, the wearing ring at the limit of its possible movement to the right should be approximately in the position shown in Figure 11, with respect to the bore of the casing, so that a small annular throttling space 68 is provided.

In my close coupled pump, I have also provided novel means whereby the same pump casing may be employed with shafts of various diameters. In the usual centrifugal pump construction, the stuffing box, indicated by the numeral 69, is made integral with the casing and since the internal diameter of the stuffing box is fixed, only one diameter of shaft may be used with each pump casing. In my construction,

the casing is provided with a threaded bore 11 into which the stuffing box 69 is removably threaded. The stuffing box is provided with a bore 12 and the shaft is provided with a sleeve 13, usually of bronze, of somewhat smaller diameter than the diameter of the stuffing box bore. A plurality of rings of packing are inserted in the annular space between the internal bore of the stuffing box and the shaft sleeve.

5 As is usual in centrifugal pumps, a pipe connection 14 is provided connected between the discharge chamber of the pump and a metal ring 15 encircling the shaft and located in the bore of the stuffing box. Sufficient pressure is applied 10 to the packing rings to enable a slight leakage of fluid to take place through the stuffing box in a direction to the right, as viewed in Figure 2, to prevent air from entering the pump. A bronze casing wearing ring 16 of the ordinary type, fixed in a bore in the stuffing box and with respect to which the hub of the impeller is rotatable may be provided, although it will be appreciated that a casing wearing ring of the type described above may be substituted if desired.

15 Upon reference again to Figures 3, 4 and 10, it will be appreciated that with the flange 38 in the position shown in Figure 3 with the discharge valve 49 set to obtain 48 gallons per minute at a total of 70 feet, the motor horsepower required by the pump will be approximately 1.6 horsepower, which, in standard motors, would require the use of a two horsepower motor unless an overloaded 1.5 horsepower motor is used. If the same pump casing is to be used 20 to obtain 16 gallons per minute at a total head of 70 feet, the flange 38 is rotated to the position shown in Figure 4. Under these conditions of operation, the pump requires less than one horsepower to drive. In this type of close coupled pump, the shaft which, as stated above, is common to both the motor and the pump, is supplied by the motor manufacturer. The shaft diameter is fixed by the manufacturer thereof in accordance with the horsepower of the motor 25 with which it is to be used. A two horsepower motor naturally requires a larger diameter shaft than a one horsepower motor. In order that the same pump casing may be used with a range of sizes of motors, it is therefore necessary that 30 the pump casing be adapted by the means described above, or equivalent thereof, so that stuffing boxes having various bore diameters may be used interchangeably with the same pump casing.

35 In the stuffing box construction described above, the packing is retained in position by a packing gland 71 which, as is quite common practice, is made in two complementary parts secured together by bolts 78. Upon removal of the bolts 40, the packing gland may be readily removed from the shaft. A solid type packing gland may be substituted, if desired, for the split and bolted type shown herein. Adjustable nut and bolt assemblies 79, extending between the stuffing box 45 and the packing gland, may be screwed up so that the part 81 which fits into the bore of the stuffing box may be pressed tightly against the packing. A bronze water singer 80, rigidly secured to the shaft by a set screw, prevents water from creeping along the shaft into the motor bearings.

50 In the close coupled pump of my construction, I have provided novel means for retaining the impeller on the shaft and, at the same time, preventing access of the liquid being pumped to

the shaft. This construction is more clearly shown in Figure 8. The shaft sleeve 73 is confined against movement along the shaft in a direction to the right, as viewed in Figure 2, by butting it against a shoulder 82 on the shaft. The other end of the shaft sleeve which, as is the usual practice, is made of bronze, has a tapered countersunk portion, as indicated at 83, so as to provide an annular bearing surface 84 of restricted area which is ground and finished. 10

A threaded bore 86 is provided in the end of the shaft along the axis thereof into which is threaded a socket head tap bolt 87 which has a suitable opening, as indicated at 88, for receiving a wrench. A sealing member or washer 89 15 is confined between the head of the bolt and the hub of the impeller. The washer is provided with an annular sealing surface 91 of restricted area which is ground and finished. The annular sealing surface 91 is the only portion of the 20 washer which engages the hub of the impeller. The washer does not engage the shaft at any point.

In practice, particularly in small pumps with which we are primarily concerned, since access 25 to the bolt must be had through the eye or suction opening of the impeller, the size of the bolt is, within rather small limits, fixed by the diameter of the impeller suction opening. Moreover, the diameter of the shaft in small pumps does 30 not permit the use of a large diameter bolt and further, as is apparent upon consideration of Figure 2, a bolt with a large diameter head restricts the free flow of water through the impeller. With these considerations, limiting the size 35 of the bolt, in mind, the bolt head and the diameter of the bolt at the root of the thread (the dimension N) are made as large as possible. Then, to obtain the maximum sealing pressure 40 between the annular sealing surface 91 of the 45 washer 89 and the hub and between the annular sealing surface 84 of the sleeve 73 and the hub, the areas of the sealing surfaces 91 and 84 are made equal to the area of the bolt at the root of the thread.

When the bolt is tightened up by a man, in the ordinary manner, so that the bolt is loaded within the elastic limit of the material of the bolt, the pressure applied on the bolt is transmitted to the sealing surfaces 91 and 84. This 50 places the maximum pressure possible at the seal points without destroying the surface contacts between the sealing surfaces and the hub. It will be appreciated that if the areas 91 and 84 are made larger than the area of the bolt at 55 the root of the thread, the pressure at the sealing surfaces will not be the maximum amount possible. If the areas 91 and 84 are made smaller than the bolt area at the root of the thread, then the pressure applied on the sealing surfaces may 60 be sufficiently great to destroy the surface contacts at the sealing surfaces. When the sealing surfaces are loaded just within their elastic limit, the whole area of the machined surfaces at the sealing points will be in contact because any 65 slight unevenness of the surfaces will be crushed out for the reason that the areas of these uneven surfaces will be less than the area of the bolt at the root of the thread and the sealing surfaces will imbed themselves slightly into the hub 70 of the impeller. The seal thus provided effectively prevents the liquid being pumped from gaining access to the shaft and is capable of withstanding a pressure of approximately 300 pounds per square inch, a pressure far above the 75

pressure which the seals may be called upon to withstand. The shaft seal described eliminates the use of troublesome packing. A copper sealing ring 93 is interposed between the head of the 5 tap bolt 87 and the washer 89 which effectively prevents leakage along the threads of the bolt. If desired, the bolt and washer may be made integral. Also if desired, instead of using a tap bolt threaded into a threaded bore in the shaft, 10 as shown herein, the end of the shaft may project slightly beyond the hub of the impeller. The projecting end may then be threaded to receive a nut and there may be interposed between the nut and the hub of the impeller a washer having 15 a sealing surface engaging the hub of the impeller.

The hub of the impeller of the pump thus far described is provided with openings 94 spaced around the hub so that the pressure on both 20 sides of the hub will be the same and the impeller will, therefore, be hydraulically balanced since the pressure in the discharge chamber on opposite sides of the impeller are the same. In Figure 9 I have shown how the shaft seal above 25 described may be applied to an impeller in which the apertures through the hub of the impeller are omitted and the impeller is, therefore, not hydraulically balanced. The construction is the same as that described above, differing therefrom 30 only in the omission of the apertures and in the omission of an impeller wearing ring corresponding to the wearing ring 76 of the structure shown in Figure 2.

It will be appreciated that I have provided a 35 novel centrifugal pump of the close coupled type which is efficient in operation, in which a novel means of sealing the drive shaft is employed and in which the characteristics of the pump may be readily varied to suit the conditions required. 40 It will further be apparent that features of my invention may be readily incorporated in other types of centrifugal pumps and that various modifications may be made in the structure shown and described without departing from the 45 spirit of my invention.

I claim:

1. In a pump of the class described, the combination of a casing having a bore defining a peripheral flange, a discharge outlet from said

casing, a volute formed in said flange and connected to the discharge outlet, a rotatable impeller having a suction inlet adjacent its center, operable in said casing and discharging liquid peripherally into said volute, a cover plate having a suction inlet in registry with the suction inlet of said impeller, said cover plate having its periphery secured to the casing flange, a flange integral with said cover plate and extending only part way around the cover plate, said flange 10 forming a shroud around the impeller and insertable in said bore, with the flangeless portion of said cover plate normally in registry with said volute portion of the casing so that liquid may freely discharge from the impeller into said volute portion of the casing, said cover plate being 15 shiftable with respect to the casing so as to change the position of the flange on the cover plate with respect to the casing volute and there- 20 by vary the characteristics of the pump.

2. In a pump of the class described, the combination of a casing having an open side and having a discharge opening, a portion of the casing adjacent said discharge opening forming a fixed cut-off, a volute extending substantially 25 from said cut-off part way around the inner periphery of the casing and discharging into the discharge opening, a rotatable impeller having a suction inlet adjacent its center operable in said casing and discharging liquid peripherally 30 into said volute, a cover plate removably secured to said casing adapted to close the open side of the casing and having a suction inlet in registry with the suction inlet of said impeller, a flange integral with and extending inward from said 35 cover plate and forming a shroud around the impeller, said flange extending only part way around the cover plate to define flange ends, the space between the ends of the flange being open and one end of the flange normally lying 40 adjacent the fixed cut-off with the opening normally in registry with said volute whereby liquid may freely discharge from said impeller into said volute, said cover plate being shiftable with respect to the casing to shift the end of the flange with respect to the fixed cut-off to thereby change the point of cut-off of the pump and vary the operating characteristics thereof.

JOHN MANN.
